SUCTION OPERATED FLOOR CLEANING TOOL

Frederick K. Minerley, Lincolnwood, Ill.

Application January 19, 1948, Serial No. 3,008

7 Claims. (Cl. 15—320)

1

This invention relates to a suction operated floor cleaning tool by which liquid such as water may be spread upon the floor to be cleaned and thereafter the liquid, together with the dirt on the floor, is drawn by suction means and deposited in a receptacle. A tool of this character is particularly advantageous in cleaning terrazzo, linoleum, marble or tile floors, and enables the cleaning operation to be accomplished efficiently and with a minimum amount of effort.

An object is to produce a new and improved tool of the above character which is adapted for hand operation and is of the self-contained type embodying a tank or reservoir containing the liquid, valve mechanisms being provided enabling liquid gravitationally to flow to the floor surface so that scrubbing thereof may be accomplished and thereafter the liquid and dirt being sucked by vacuum means back into the tank, leaving the floor surface almost dry.

Another object is to improve the construction of a tool of the above character enabling it to be manufactured on large scale production economically, the parts in the main being fabricated from sheet metal.

A further object is to produce a tool of the above character, when it is laid down upon a supporting surface and connected to a source of vacuum, the liquid within the reservoir will not be sucked therefrom.

Other objects and advantages of the invention will hereinafter appear, and for purposes of illustration but not of limitation, an embodiment of the invention is shown on the accompanying drawings, in which

Figure 1 is a side elevation of the tool in position of use;

Figure 2 is an enlarged longitudinal sectional elevation of the body of the tool;

Figure 3 is a side elevation of the tool resting upon a supporting surface in its inoperative position;

Figure 4 is a transverse sectional view on the line 4—4 of Figure 2;

Figure 5 is a fragmentary sectional view of the lower portion of the body of the tool showing the valve in open position enabling liquid within the tank to flow gravitationally to the floor surface;

Figure 6 is a sectional view of the floor tool; and

Figure 7 is a bottom plan view of a modified form of the floor tool.

The illustrated embodiments of the invention comprise a hand operated tool for use in connection with the cleaning or scrubbing of floors, the same being admirably adapted for cleaning linoleum, tile floors or the like, but is also suitable for cleaning carpeted floors or other similar floor coverings. In this instance, the tool is adapted to be connected by a flexible hose 10, to a portable type vacuum cleaner, or other suction producing source. As shown, the flexible hose is detachably connected to an elongate metal tube 11 which curves downwardly and then has a straight

portion which extends longitudinally and concentrically through an elongate sheet metal tank or reservoir 12 having a cylindrical body 13, the opposite ends of which are closed by dome-like end portions 14 and 15 which are not only permanently and in fluid-tight contact with the tube 11, but also with the adjacent end portions of the tank or reservoir.

As shown, the end portions 14 and 15 have flanged ends which snugly embrace and may be soldered, welded or otherwise secured in fluid-tight manner to the outer surface of the tube 11. The tank or reservoir 12 is adapted to contain liquid such as water. The drawing illustrates the approximate amount which is preferably desired within the tank, it being understood that the tank is only partially filled with the liquid, the opening being closed by a gap 16 in the end portion 15 enabling water to be introduced into the tank or emptied therefrom.

The tube 11 terminates a short distance beyond the bottom end closure 15 and detachably connected to such projecting end portion is a tube 17, the lower end portion 18 of which is curved in the opposite direction and swivelly connected to the outer end portion thereof is a floor tool 19. The floor tool 19 in this instance is hollow and is provided with downwardly extending bristles 20 disposed in an oblong row. It is to be understood that liquid may pass from the tank 12 through the tube 17 to the central portion of the floor tool and associated with the floor tool may also be, as shown in Fig. 7, a rubber squeegee 21 as shown in Fig. 6. Manifestly other forms of floor tools may be used such, for example, as sponge, fabric, or the like, as may be desirable in the scrubbing or cleaning of hard floor or carpeted surfaces.

Near the bottom of the tank 12, a port 22 is formed in the tube 11 which, when open, allows liquid within the reservoir to flow gravitationally to the floor tool 19. Controlling this port is a valve 23 which is connected to one end of an arm 24 pivoted intermediate its ends to a bracket 25, the latter being mounted on the outside of the tube 11. A coil spring 26 engages the opposite end of the arm 24 normally to urge the valve 23 to its seat to close the port 22. The arm 24 has a lateral extension 27 to which one end of a wire 28 is connected.

Spaced above the port 22 and disposed approximately midway of the length of the tank 13 are a plurality of openings 29. These openings are arranged above the level of the liquid within the tank not only when the tool is in its upwardly inclined position of use, but also when the tool is laid upon a supporting surface as indicated in Figure 3. The openings 29 are enclosed by a bell-shaped baffle 30, the walls of which are spaced from the tube 11 and the upper end of which is suitably secured to the outer surface of the tube.

Above the openings 29, a plug 31 of any suit-

able construction is disposed within the tube to militate against liquid drawn upwardly in the tube and discharged into the tank through the openings 29 from passing thereabove, as will hereinafter appear. In this instance, a flanged disc forms the plug 31 and is conveniently secured in position by a press fit. Also formed in the tube 11 in the region above the plug 31 and within the tank 12, is an annular row of elongate openings 32 through which air within the tank 12 is evacuated in response to the suction created by the portable vacuum cleaner or source of suction, referred to above. It is manifest that when the valve 23 is in closed position and a partial vacuum is created within the tank 12, the liquid and dirt from the floor is quickly sucked or drawn through the floor tool 19, tube 17, tube 11 and discharged through the openings 29, into the tank, the baffle 30 militating against the liquid entrained in the air from passing through the openings 32. This enables the liquid and dirt on the surface to be cleaned to be quickly and readily removed, leaving such surface almost dry.

It is manifest that after a partial vacuum exists within the tank 12, liquid will not gravitationally flow from the tank even upon opening the valve 23. Therefore, in order to allow such gravitational flow of liquid, the source of suction must be either shut off or relieved. For this purpose, an opening 33 is formed in the tube 11 in the portion above the tank 12 and a valve 34 disposed on the outside of the tube in the form of a flap partially embracing the tube is adapted to cover or uncover the opening 33. Manifestly, when the valve 34 is in closed position and the valve 23 is likewise closed, a stream of air would pass through the floor tool 19 up the front end of the tube or wand 17 to the tube 11, thence laterally into the tank through the openings 29 and thence from the tank through the openings 32. As above pointed out, any liquid and dirt drawn into the tank by the air will drop into the tank while the air will continue its movement from the tank.

When it is desired to flow a quantity of liquid on the floor surface, both valves 34 and 23 are opened. Thus air is drawn by the source of suction through the opening 33 without withdrawing air from the tank 12. At that time, liquid may flow by gravity from the tank 12 through the tube 17 to the floor tool 19. Such gravitational flow is made possible since the interior of the tank 12 is not under subatmospheric pressure.

By slightly opening the valve 34 without unseating the valve 23, the tool may be used for scrubbing purposes without additional flow of liquid. The liquid on the floor may then be brushed or scrubbed into the floor surface to collect the dirt and other foreign particles.

To effect conjoint operation of the valves 23 and 34, a fine wire 35 leads from the extension 27 of the valve arm 24 through a portion of the tank 12, into the tube 11 through one of the openings 32 through a curved guide tube 36 to an arm 37 which is pivoted to a bracket on the outside of the tube 11. The arm 37 has a finger piece 38 to facilitate actuation thereof. It will be understood that by actuating the arm 37 to the position indicated in Figure 1, both the valves 23 and 34 are unseated thereby enabling the liquid to flow gravitationally to the floor tool as above indicated. When the finger piece 38 is released, the coil spring 26 moves both valves to closed position, whereupon the liquid may be

drawn from the floor and deposited into the tank 12 as above indicated. Also by a slight movement of the finger piece 38, the valve 34 may be slightly opened sufficient to relieve the tank 12 of its subatmospheric pressure but insufficient to unseat the valve 23, thereby enabling scrubbing to be accomplished.

From the above description, it will be manifest that I have produced an exceedingly simple and efficient tool for cleaning hard smooth surfaces such as linoleum, tile, terrazzo and the like but which also can be advantageously used for cleaning carpeted or similar surfaces. The tool can be made in the main from sheet metal on a quantity basis very economically. The simplicity of operation lends itself to use in the home without particular instruction. Since the liquid can be re-used, it is not necessary that a constant source of liquid be available. One feature of importance is the tapered shape of the tank which prevents the liquid from finding its way into the tube 11 and thereby drawn by the source of suction from the tool.

Reference is hereby made to my co-pending application Serial No. 664,626, filed April 24, 1946, and entitled "Suction Operated Floor Cleaning Device Employing Liquid."

It is to be understood that numerous changes in details of construction, arrangement and operation may be effected without departing from the spirit of the invention, especially as defined in the appended claims.

What I claim is:

1. In a floor cleaner including a floor tool, an elongate tank providing a liquid reservoir, substantially rigid tube means providing a connection between the floor tool and one end of said tank, said tube means extending generally upwardly from the floor tool during normal use of the cleaner and disposed longitudinally through said tank, a port in said tube means adjacent one lower end of said tank enabling liquid to flow gravitationally from said tank to said floor tool, a valve controlling said port, an opening in said tube means above the liquid level in said tank through which liquid may be returned to the tank from the floor tool, a plug for said tube means above said last opening, an opening in said tube means above said plug to enable air evacuation of the inside of said tank for drawing liquid from said floor tool, an opening in said tube means outside of and above said tank, a valve for said last opening, said tube means beyond said last opening being adapted to be connected to a source of suction, and means for conjointly operating said valves.

2. In a floor cleaner including a floor tool, an elongate tank providing a liquid reservoir, substantially rigid tube means providing a connection between the floor tool and one end of said tank, said tube means extending generally upwardly from the floor tool during normal use of the cleaner and disposed longitudinally through said tank, a port in said tube means adjacent the lower end of said tank enabling liquid to flow gravitationally from said tank to said floor tool, a valve controlling said port, an opening in said tube means above the liquid level in said tank through which liquid may be returned to the tank from the floor tool, a plug for said tube means above said last opening, an opening in said tube means above said plug to enable air evacuation of the inside of said tank for drawing liquid from said floor tool, a baffle disposed between said last two openings, an opening in said

tube means outside of and above said tank, a valve for said last opening, said tube means beyond said last opening being adapted to be connected to a source of suction, and means for conjointly operating said valves.

3. In a floor cleaner including a floor tool, an elongate tank providing a liquid reservoir, substantially rigid tube means providing a connection between the floor tool and one end of said tank, said tube means extending generally upwardly from the floor tool during normal use of the cleaner and disposed longitudinally through said tank, a port in said tube means adjacent the lower end of said tank enabling liquid to flow gravitationally from said tank to said floor tool, a valve controlling said port, an opening in said tube means above the liquid level in said tank through which liquid may be returned to the tank from the floor tool, a plug for said tube means above said last opening, an opening in said tube means above said plug to enable air evacuation of the inside of said tank for drawing liquid from said floor tool, a baffle disposed between said last two openings, an opening in said tube means outside of and above said tank, a valve for said last opening, said tube means beyond said last opening being adapted to be connected to a source of suction, and means for conjointly operating said valves, said operating means including a cable extending through a portion of said tube means and said tank, and a finger piece on said last valve.

4. In a floor cleaner including a floor tool, an elongate tank providing a liquid reservoir, substantially rigid tube means providing a connection between the floor tool and one end of said tank, said tube means extending generally upwardly from the floor tool during normal use of the cleaner and disposed longitudinally through said tank, a port in said tube means adjacent the lower end of said tank enabling liquid to flow gravitationally from said tank to said floor tool, a spring-tensioned valve controlling said port, an opening in said tube means above the liquid level in said tank through which liquid may be returned to the tank from the floor tool, a plug for said tube means above said last opening, an opening in said tube means above said plug to enable air evacuation of the inside of said tank for drawing liquid from said floor tool, a baffle in the form of a bell surrounding said tube means disposed between said last two openings, an opening in said tube means outside of and above said tank, a valve for said last opening, said tube means beyond said last opening being adapted to be connected to a source of suction, and means for conjointly operating said valves, said operating means including a cable extending through a portion of said tube means and said tank, and a finger piece on said last valve.

5. In a floor cleaner including a floor tool, an elongate tank providing a liquid reservoir, substantially rigid tube means providing a connection between the floor tool and one end of said tank, said tube means extending generally upwardly from the floor tool during normal use of the cleaner and disposed longitudinally through said tank, a port in said tube means adjacent the lower end of said tank enabling liquid to flow gravitationally from said tank to said floor tool, a spring-tensioned pivotally mounted valve controlling said port, an opening in said tube means above the liquid level in said tank through which liquid may be returned to the tank from the floor tool, a plug for said tube

means above said last opening, an opening in said tube means above said plug to enable air evacuation of the inside of said tank for drawing liquid from said floor tool, an opening in said tube means outside of and above said tank, a valve pivotally mounted on the outside of the tube means for said last opening, said tube means beyond said last opening being adapted to be connected to a source of suction, and means for conjointly operating said valves.

5 6. In a floor cleaner including a floor tool, an elongate tank providing a liquid reservoir, substantially rigid tube means providing a connection between the floor tool and one end of said tank, said tube means extending generally upwardly from the floor tool during normal use of the cleaner and disposed longitudinally through said tank, a fluid-tight connection between opposite ends of said tank and said tube means, a port in said tube means adjacent the lower end of said tank enabling liquid to flow gravitationally from said tank to said floor tool, a valve controlling said port, an opening in said tube means above the liquid level in said tank through which liquid may be returned to the tank from the floor tool, a plug for said tube means above said last opening, an opening in said tube means above said plug to enable air evacuation of the inside of said tank for drawing liquid from said floor tool, an opening in said tube means outside of and above said tank, a valve for said last opening, said tube means beyond said last opening being adapted to be connected to a source of suction, and means for conjointly operating said valves.

20 7. A cleaner of the character described, comprising: a floor tool; a substantially rigid tube connected to the floor tool and extending upwardly therefrom during normal use of the cleaner; a tank supported on the tube above the floor tool, the tube extending through the tank and having an upper portion extending thereabove; said tube having a port in the side wall above the lower end of the tank, a first aperture through the side wall thereof above said port and within the tank, a second aperture through the side wall thereof above the first aperture and within the tank, and a partition blocking said tube between the apertures; the upper portion of the tube being adapted for connection with a source of suction; valve means actuatable for respectively opening and closing the port; suction control means actuatable for controlling the suction applied to the upper portion of the tube; and manually operable actuating means for actuating said valve and suction control means.
